UNITED STATES PATENT OFFICE.

OLIVER S. SLEEPER, OF BUFFALO, NEW YORK, ASSIGNOR TO BUFFALO FOUNDRY & MACHINE COMPANY, OF BUFFALO, NEW YORK, A CORPORATION OF NEW YORK.

DRYING-MACHINE.

1,103,443.

Specification of Letters Patent. Patented July 14, 1914.

Application filed October 2, 1912. Serial No. 723,498.

To all whom it may concern:

Be it known that I, OLIVER S. SLEEPER, a citizen of the United States, residing at Buffalo, in the county of Erie and State of New York, have invented new and useful Improvements in Drying-Machines, of which the following is a specification.

This invention relates to a vacuum drier of that type in which the material to be dried is deposited on the periphery of an internally heated drum which is arranged in a shell or casing from which the vapors are exhausted to produce a vacuum in the same.

It is the object of this invention to so construct and mount the drum and inclosing casing so that they may be separated easily and conveniently to permit of thoroughly cleaning the working surfaces of the drum and casing and rendering the same perfectly sanitary so that the product thereof is pure and wholesome.

In the accompanying drawings consisting of 2 sheets: Figure 1 is a vertical longitudinal section of a drying machine embodying my invention. Fig. 2 is a vertical transverse section thereof taken in line 2-2, Fig. 1.

Similar characters of reference indicate corresponding parts in both views.

1 represents the bed or base of the machine which may be of any suitable construction to support the working parts of the machine but which preferably has an elevated front part 2 and a depressed rear part 3. Between the elevated and depressed parts of the base the same is provided with a standard 4 the upper part of which is constructed to form the rear fixed head 5 of

the casing or shell forming the vacuum or drying chamber 6 and this standard is also provided with a horizontal rear bearing 7 which is arranged axially relatively to the rear head of the casing. The body 8 of the shell is detachably secured at its rear end to the rear head by bolts 9 or otherwise and provided at its front end with an integral head 10 containing a horizontal front bearing 11 which is arranged horizontally in line with the rear bearing 7. The upper part of the body of the casing is of substantially semi-cylindrical form while the lower part thereof is constructed to form a catch basin 12 and an outlet passage 13 which are arranged lengthwise side by side. The body

and front head are mounted on the base so that when detached from the rear head the same may be moved horizontally for rendering the interior of the same and the parts normally inclosed thereby accessible for cleaning, inspection and repairs. For this purpose supporting wheels 13¹ are preferably pivoted on the lower part of the body of the casing and the upper side of the elevated part of the base is provided with a pair of horizontal longitudinal tracks 14 upon which said wheels run. By this means the body and front head of the casing when free may be easily moved toward and from the rear head. While the machine is in use the rear end of the movable part of the casing is secured to the rear head by the bolts 9 and at this time the front part is also securely held against displacement by a front fastening device which preferably comprises a clamping bolt 15 which is pivoted at its lower end to the elevated part of the base so as to swing vertically while the screw nut 16 at its upper end bears against a bifurcated lug 17 on the lower front part of the movable section of said casing. Upon tightening the nut 16 the supporting wheels 13¹ are drawn firmly against the tracks 14 and the casing is held reliably in place while upon detaching the bolt 15 from the casing the movable part of the latter is free to be shifted horizontally relatively to the fixed part thereof.

A partial vacuum is created within the chamber of the casing by means of an exhausting device of any suitable construction which is connected with a vapor outlet 18 formed preferably in the upper part of the fixed rear head of the casing.

19 represents a hollow drying drum preferably of metal having the form of a cylinder which rotates horizontally within the vacuum chamber and which is adapted to be heated by admitting steam or other heating medium to the interior thereof and to receive on its periphery the liquid material which is to be dried. This drum is provided on its rear head 20 with a driving shaft 21 which is journaled in the rear bearing 7 while its front head 22 is provided with a trunnion 23 which is journaled in the front bearing 11 of the casing, the last mentioned bearing being closed at its outer end so as to avoid leakage from the outer atmosphere into the vacuum chamber at this place.

The drum is turned clockwise in Fig. 2 so that its lower side moves from the discharge passage to the catch basin which movement may be effected by any suitable means, for instance by a driving mechanism which comprises a gear wheel 24 secured to the outer end of the shaft 21. The steam is supplied to the interior of the drying drum by a stationary supply pipe 25 passing axially through the shaft 21 which is made hollow for this purpose and of a bore somewhat larger than the diameter of the steam supply pipe, and a stationary coupling sleeve 26 surrounding the outer part 10 of the steam pipe and connected at its outer end therewith while its inner end passes through a stuffing box 27 at the outer end of the hollow driving shaft. The water of condensation is picked up from the interior 15 of the drying drum by a scoop 28 secured lengthwise to the bore thereof, and a curved outlet pipe 29 which conducts the water from the scoop to the inner end of the hollow driving shaft 21, from which latter the water is withdrawn by the coupling sleeve 25 or tube 26 having an outlet opening 30.

The liquid or wet material to be dried is presented to the underside of the drum by a pan or tray 31 which holds the liquid so that the periphery of the drum dips into the same and picks up a thin film of the liquid. As the drum rotates this film of liquid is carried over the top of the same and is dried during this time owing to the heat in the 35 drum and while the dried film passes the discharge passage the film is scraped from the periphery of the drum into the discharge passage by a blade or knife 32 which is arranged between this passage and the catch 40 basin, thereby clearing the drum preparatory to receiving another coat of material to be dried.

The delivery pan is mounted at its rear end on the rear head of the casing, as shown 45 at 33, but is disconnected from the movable parts of the latter. The supply of liquid is carried in the catch basin and is delivered from the same to the pan by a pump 34 mounted on the depressed rear part of the base and having its inlet connected with the lower part of the catch basin by a pipe 35 containing a coupling or union 36 while its outlet is connected with the rear end of the delivery pan by a pipe 37 containing a coupling or union 38. This pump is so operated that it delivers more liquid to the pan than the drum is capable of picking up whereby the liquid flows constantly in the form of a stream across said pan and the 50 excess liquid overflows from the pan and drops back again into the catch basin ready to be again pumped into the pan, thereby keeping the undried liquid constantly in circulation and agitated so that the solid material in the same remains in suspension and 55

will not precipitate before reaching the drum.

The dried material scraped from the drum into the discharge passage is delivered by the latter into a receiver or box 39 which is 70 mounted on the movable part of the casing so as to travel therewith and which is provided with an inlet valve or cover 40 and an outlet valve or cover 41. When it is desired to empty the receiver its inlet valve 40 75 is first closed so as to cut the same off from the vacuum chamber and then the outlet cover 41 may be opened for removing the dried material from the receiver.

When it is desired to clean the machine 80 the bolts 9 and 15 are disconnected and the unions 36, 38 are uncoupled. The body and front head of the casing and also the receiver carried by the casing are now moved forwardly on the tracks 14 from the position shown by full lines in Fig. 1 to the position shown by dotted lines in the same figure, in which last mentioned position the body of the casing is entirely separated and 85 clear from the drum. All parts of the interior of the casing, the exterior of the drum, the delivery pan and connecting parts are easily and conveniently accessible so that they may be thoroughly cleaned, inspected and repaired or adjusted. This is particularly desirable when drying materials which are liable to ferment or become sour or putrid if not taken care of such as milk. After cleaning, adjusting and repairing the 90 casing may be again quickly and easily assembled with the drum and pan and the connections between the pump and the pan and catch basin restored for resuming the normal operation of the machine.

I claim as my invention:

1. A drying machine comprising a drying drum adapted to receive the material to be dried on its outer surface, and a casing inclosing said drum, said drum and casing being separable axially to afford access to 100 the interior of the machine.

2. A drying machine comprising a drying drum adapted to receive the material to be dried on its outer surface, and a casing inclosing said drum, said casing having a part which is removable axially from said drum for rendering the interior of the machine accessible.

3. A drying machine comprising a drying drum adapted to receive the material to be dried on its outer surface, and a casing inclosing said drum, said casing having a body which is movable lengthwise of the drum for rendering the interior of the machine accessible.

4. A drying machine comprising a drying drum adapted to receive the material to be dried on its outer surface, and a casing inclosing said drum and comprising a fixed head, a movable body detachably connected 110

at one end with said fixed head and provided at its opposite end with a head which is movable with the body.

5. A drying machine comprising a base, a standard rising from the base and provided with a fixed bearing and with a fixed head, a longitudinally movable tubular body detachably secured at one end to said fixed head and provided at its other end with a movable head, said body and heads forming an inclosing casing, and a drum rotatable in said casing and adapted to receive the material to be dried on its periphery.

6. A drying machine comprising a base, a standard rising from the base and provided with a fixed bearing and with a fixed head, a longitudinally movable tubular body detachably secured at one end to said fixed head and provided at its other end with a movable head, said body and heads forming an inclosing casing, a drum rotatable in said casing and adapted to receive the material to be dried on its periphery and provided with a shaft journaled in said bearing.

25 7. A drying machine comprising a base, a standard rising from the base and provided with a fixed bearing and with a fixed head, a cylindrical body detachably secured at one end to said fixed head and provided at its other end with a movable head having a movable bearing, said body and heads forming an inclosing casing, and a rotatable drum arranged in said casing and provided at one end with a shaft journaled in said fixed bearing and at its other end with a trunnion journaled in said movable bearing.

8. A drying machine comprising a base, a standard rising from the base and provided with a fixed bearing and with a fixed head, a longitudinally movable tubular body detachably secured at one end to said fixed head and provided at its other end with a movable head, said body and heads forming an inclosing casing, a drum rotatable in said casing and adapted to receive the material to be dried on its periphery, a track arranged on said base, and wheels arranged on said movable part of the casing and running on said track.

50 9. A drying machine comprising a base, a standard rising from the base and provided with a fixed bearing and with a fixed head, a cylindrical body detachably secured at one end to said fixed head and provided at its other end with a movable head, said body and heads forming an inclosing casing, a drum rotatable in said casing, a track arranged on said base, wheels arranged on said movable part of the casing and running on said track and means for clamping said movable part of the casing on said base.

10. A drying machine comprising a base,

a standard rising from the base and provided with a fixed bearing and with a fixed head, a cylindrical body detachably secured at one end to said fixed head and provided at its other end with a movable head, said body and heads forming an inclosing casing, a drum rotatable in said casing, a track arranged on said base, wheels arranged on said movable part of the casing and running on said track and means for clamping said movable part of the casing on said base comprising a bolt pivoted on said base and having its nut engaging with a shoulder on said movable part of the casing.

11. A drying machine comprising a base, a standard rising from the base and provided with a fixed bearing and with a fixed head, a longitudinally movable tubular body detachably secured at one end to said fixed head and provided at its other end with a movable head, and at its side with a discharge passage, said body and heads forming an inclosing casing and adapted to receive the material to be dried on its periphery, a drum rotatable in said casing and a receiver connected with the movable part of said casing and communicating with said passage.

12. A drying machine comprising a base, a standard rising from the base and provided with a fixed bearing and with a fixed head, a cylindrical body detachably secured at one end to said fixed head and provided at its other end with a movable head, said body and heads forming an inclosing casing, a drum rotatable in said casing, and means supplying liquid to the periphery of the drum comprising a pan mounted on the standard and arranged to support a body of liquid for engagement by the underside of said drum.

13. A drying machine comprising a base, a standard rising from the base and provided with a fixed bearing and with a fixed head, a cylindrical body detachably secured at one end to said fixed head and provided at its other end with a movable head, said body and heads forming an inclosing casing, a drum rotatable in said casing, and means supplying liquid to the periphery of the drum comprising a pan mounted on the standard and arranged to support a body of liquid for engagement by the underside of said drum, and a pump detachably connected with said pan and the lower part of the body of the casing.

Witness my hand this 30th day of September, 1912.
